(57) **CLAIM**

The ornamental design for a multi-function vehicle oval light assembly, as shown and described.

DESCRIPTION

FIG. 1 is a front perspective view of a multi-function vehicle oval light assembly of the present invention;

FIG. 2 is a rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof, the bottom view being a mirror image thereof.
